INSULATED CHEST

David Edward Roche, Nashua, N.H., assignor to
Family Products, Inc., Tyngsboro, Mass.

Filed Dec. 14, 1972, Ser. No. 315,209

Term of patent 14 years

Int. Cl. D7—01

U.S. Cl. D7—77

FIG. 1

FIG. 2

FIG. 4

FIG. 3

FIG. 5

FIG. 6

FIG. 7

FIG. 1 is a perspective view of an insulated chest showing my new design with the handle in the extended position;

FIG. 2 is a front view thereof;

FIG. 3 is a right end view thereof;

FIG. 4 is a left end view thereof;

FIG. 5 is a top view thereof;

FIG. 6 is a bottom view thereof; and

FIG. 7 is a fragmentary perspective view on an enlarged scale of the hinge area thereof.

I claim:

The ornamental design for an insulated chest, as shown and described.
